UNITED STATES PATENT OFFICE.

JOHN H. HUNT, OF DAYTON, OHIO, ASSIGNOR TO THE DAYTON ENGINEERING LABORATORIES COMPANY, OF DAYTON, OHIO, A CORPORATION OF OHIO.

SUCTION BURNER.

Application filed April 26, 1922. Serial No. 555,670.

To all whom it may concern:

Be it known that I, JOHN H. HUNT, a citizen of the United States of America, residing at Dayton, county of Montgomery, 5 State of Ohio, have invented certain new and useful Improvements in Suction Burners, of which the following is a full, clear, and exact description.

This invention relates to apparatus for 10 preheating engine fuel mixtures such as supplied by carburetors in order to facilitate engine starting especially in cold weather.

It is an object of the present invention to apply heated combustion products from a 15 liquid fuel burner directly to the air going into the carburetor and particularly to apply heat as close as possible to the carburetor jet. In carrying out this invention I employ a liquid fuel burner which is operated by engine suction and consumes engine fuel, the fuel being conducted to the burner preferably directly from the fuel bowl.

A further object is to control the burner 20 suction automatically so as to restrict its range of variation in order that the operation of the burner may not substantially interfere with the operation of the engine. A further object is to supplement this automatic control with a manual control by means of which the rate of combustion of the burner may be varied at will.

A further object is to provide a manual control by means of which the burner may 25 be rendered inoperative.

A further object is to provide means for compensating for the effect on the engine fuel mixture by the discharge of exhaust gases from the burner into the carburetor 30 intake. It is the aim of the invention to keep the proportions of the engine fuel mixture as nearly constant as possible.

Other and further objects of the present invention will be apparent from the following description, reference being had to the accompanying drawings, wherein a preferred embodiment of the present invention is clearly shown.

In the drawings:

Fig. 1 is a sectional view of a carburetor and apparatus for heating the intake thereof which is constructed in accordance with the present invention:

Fig. 2 is a plan view partly in section of the apparatus shown in Fig. 1; and

Fig. 3 is a chart including curves which represent variation in suction in different parts of the apparatus.

In the drawings, 20 designates the intake manifold of the engine provided with a passage 21 which leads to the various cylinders of the engine not shown. To the manifold 20 is secured a carburetor 22 by means of bolts 23. Carburetor 22 may be of any type which is adapted to handle the usual automobile fuels. For purposes of illustration the Hudson type of carburetor is shown, this carburetor being one used with a well-known make of automobile. Carburetor 22 includes a horizontal passage which comprises an intake portion 24, a nozzle chamber 25 and a throttle chamber 26. Directly over the nozzle chamber 25 is located a cylinder 27 in which reciprocates a piston 28, the movement of which is produced by variations in engine suction, the cylinder 27 being in communication with the throttle chamber 26 through a passage 29. To the piston 28 is attached a metering pin 30 having a tapered metering groove 31. The grooved portion of the pin 30 projects into a nozzle 32 which is adjustable vertically by means of a lever 33, transmitting motion to the nozzle 32 through a shaft 34 carrying a gear, not shown, which meshes with a rack 35 formed on the nozzle 32. The pin 30 and nozzle 32 are in communication with a fuel well 36 into which fuel is delivered through a pipe 37 from a fuel bowl 38 provided with the usual type of float control valve which limits the quantity of fuel delivered to the bowl from an outside source. As the action of this type of carburetor is well-known in the art, further description thereof is considered unnecessary. It is sufficient to state that as the suction in the cylinder 27 increases with the opening of the throttle valve 26, the piston 28 will lift the metering pin 30 and control the throat of the nozzle chamber 25 in such a manner as to tend to effect substantially constant fuel mixture proportions over a wide variation of engine speed.

The carburetor intake 24 is in direct communication with a regulating chamber 40 provided in a regulator frame 41 which is

directly supported by the carburetor 22. Frame 41 supports a valve port member 42 having brackets 43 supporting a bearing 44 within which slides a cylinder 45 entirely closed at its upper end and closed at its lower end by a cap 46 which is held in position by means of a screw 47. Within the cylinder 45 slides a disc 48 attached to the upper end of a rod 49 which passes through a central aperture of the cap 46 and is attached at its lower end to a valve 50. A spring 51 is interposed between the cap 46 and the disc 48 for the purpose of yieldingly maintaining the valve 50 upon the seat 52 provided on the port member 42. The upper end of cylinder 45 supports a lug 53 carrying a stud 55 which is attached by link 57 to stud 58 carried by a bell crank lever 59 which is pivoted on stud 60 carried by the bearing portion 44 of port member 42. One arm 61 of the lever 59 carries the stud 58 and the other end 62 may be connected in any suitable manner with a control handle, not shown, which is preferably located on the automobile dashboard within convenient reach of the driver. Opposite the port member 42, the regulator frame 41 is provided with a relief valve opening 70 surrounded by an annular flange 71 which provides a seat for the relief valve 72 which is preferably a disc attached to the lower end of a rod 73. Rod 73 is slidable within a bearing provided by a boss 74 supported centrally of the aperture 70 by means of spaced ribs 75. Valve 72 is normally held in yielding engagement with the seat 71 by means of a spring 76 interposed between the upper end of the boss 74 and a washer 77 retained upon the upper end of the rod 73 by means of a pin 78.

The regulator frame 41 is formed to provide a flame chamber 80 in direct communication with the combustion chamber 81 of a liquid fuel burner designated as a whole by 82. Burner 82 comprises a burner frame 83 which is attached to the frame 41 in any suitable manner as by means of bolts 84. The combustion chamber 81 referred to is provided within a burner insert 85, the interior of which is substantially continuous with the fuel jet chamber 86.

Referring to Fig. 2, a metering well 87 is in communication with the liquid fuel in the carburetor bowl 38 and this metering well includes devices which provide, when activated by engine suction, a mixture of air and fuel which is sucked up through the pipe 88 to the burner nozzle 89. As the exact construction of this metering well does not of itself constitute a part of the present invention, but is more particularly claimed and described in the copending application of John H. Hunt and John T. Fitzsimmons, Serial No. 495,024, filed Aug. 24, 1921, it is thought unnecessary to illustrate and de-

scribe this metering well. For the purpose of disclosing the present invention, it is thought sufficient to state that the metering well provides a relatively rich mixture of fuel and air which will light readily by means of an electric spark, and the metering well provides that the proportions of air and fuel in this rich lighting mixture shall remain substantially constant over a wide variation of engine suction. 76

As this mixture enters the nozzle 89 it separates itself, due to the action of gravity, into lighter and heavier constituents, the heavier portion trickling down the annular passage 90 which surrounds the nozzle insert 91, while the lighter constituents pass through holes 92 into the central passage 93 of the insert 91. These lighter portions of the fuel mixture meet with the heavier portions coming out between the lower end of the insert 91 and the nozzle member 89, and assist in breaking up the fuel into small particles as it passes out through the nozzle orifice 94. This fuel mixture is ignited by spark passing across the points 95 and 96 of the spark plug 97, producing a flame which, due to the suction of the engine, is caused to project itself through the combustion chamber 81 and the heated carbon particles are caused to be consumed by oxygen and the air entering the chamber through holes 98 leading into the chamber 81 through the insert 85 from an air distributing chamber 99. Chamber 99 is in communication with outside air through the passage 100 which leads around the nozzle member 89 and the quantity of air entering the passage 100 is controlled by means of a screw 101. 102 designates a mica window for observing the character of the flame. 103 designates a plug providing a puddle cavity 104. In case the burner does not light readily liquid fuel from the nozzle 89 may collect in this cavity 104. Due to the suction of the engine, air will enter into this cavity 104 through a small hole 105 causing the bubbling of air through this puddle of fuel in such a way as to break it up into small particles with the result that it may be readily ignited by the electric spark. 110 This type of fuel burner is described and claimed in the copending application of John H. Hunt, John T. Fitzsimmons and George F. Embshoff, Serial No. 484,049, filed July 12, 1921, and it is thought that further description is unnecessary. It is to be understood that other types of suction burners can be used in connection with the regulating apparatus described. 115 120

The flame from the burner 82 may extend through the passage 81 and into the flame chamber 80 and impinge upon the wall of the regulator casting 41, thereby heating up the air which enters the chamber 40. The products of combustion of the burner pass 125

from the chamber 80 through a small tube 110, preferably a quarter of an inch in internal diameter, which extends into the intake portion 24 of the carburetor and preferably 5 along the bottom thereof so that the hot gases from this tube 110 may impinge directly upon any liquid fuel which may collect in the bottom of the nozzle of the carburetor.

10 Ignition for the burner plug 97 is provided by a battery 111 connected with an ignition coil 112 through a switch 113 and timer 114.

The engine is cranked in any suitable manner, and during this cranking period, 15 the valve 50 will open, due to the suction in the chamber 40. The opening of this valve is limited, however, by the action of the spring 51, the amount of initial compression in this spring being such that during 20 the cranking of the engine the suction for the burner 82 will be sufficient to produce in the burner the required amount of combustion for heating up the carburetor passages sufficiently for engine starting. The suction in the chamber 40 increases with increasing engine speed for a given throttle opening and consequently the opening of the valve 50 increases. It is intended that the spring 51 shall control the valve 50 in such 25 a manner that the suction in chamber 40 will be relieved by the incoming air in such a manner that the range of variation in burner suction will be restricted. It is not necessary that the burner suction be uniform.

30 The burner suction at wide open throttle may be two or three times the suction at engine idling without seriously affecting the operation of the engine. In case it is desired to vary the rate of combustion of the burner, the lever 59 may be operated in such a manner as to move the cylinder 45 upwardly as viewed in Fig. 1, thereby increasing the initial compression of the spring 51. If this compression is increased, 35 it is evident that the suction in chamber 40 will be increased so that the flame produced by the burner 82 will increase in intensity. To decrease the intensity of the flame again, the cylinder 45 is moved down-

40 wardly by means of the lever 59 and the dash control which may be connected therewith. When it is desired to render the burner inoperative, the switch 113, controlling the burner ignition, is opened and the cylinder 45 is moved downwardly to such 45 an extent that the lower end of the rod 49 engages the rod 73 and pushes the valve 72 open. By having the chamber 40 open to atmosphere through the relatively large openings at the top and bottom of the flame 50 41, practically no suction will be placed upon the burner 82 and therefore no fuel will be sucked up through the nozzle 89.

In case of back fire through the carburetor, the valve 72 acts as a relief valve and

thereby prevents any back pressure through the burner which would cause liquid fuel to be forced back through the pipe 88 and out through the metering well 87 and into the carburetor float bowl 38.

70

It is evident that if the carburetor is adjusted to provide the proper fuel mixture for engine idling, the mixture will tend to run lean as the load on the engine increases, the engine speed remaining the same. 75 The carburetor may be adjusted so that the proportions of liquid fuel drawn up through the jet 32 and the proportion of gaseous matter entering the intake 24 will be substantially constant over a relatively wide 80 range of engine suction. Yet as the throttle valve is opened to provide for increased engine load, the amount of oxygen supplied to the carburetor will increase faster than the amount of liquid fuel drawn up through 85 the nozzle 32. This happens because the burner combustion is restricted to a limited variation during a wide variation of engine suction and hence the diluting of the air does not increase in proportion to the quantity of air drawn into the carburetor. It is, of course, obvious that if the carburetor would be set to give the proper mixture for full load at a certain engine speed then the carburetor would run over rich when idling. 90

To overcome this difficulty, the carburetor float bowl is sealed instead of being open to atmosphere as in usual practice, and this bowl is connected through passage 120 with a pipe 121 which leads into the carburetor 95 22 at 122 between the throttle valve 26^a and the engine intake 21. Between the passage 120 and the outlet 122, the pipe 121 is provided with a restricted hole 123. Pipe 121 is in communication with the intake 100 24 of the carburetor at 123. Between the passage 120 and the outlet 125, the pipe 121 is provided with an adjustable needle valve 126 by means of which the relative 105 areas of the passage 123 and the area of the opening around the valve 126 may be varied. The effect of this variation is shown graphically in Fig. 3. The curve A represents variation in suction corresponding to variation in engine load for a given engine speed within the engine intake marked A in Fig. 1. The curve B represents the corresponding 110 variations in suction in the nozzle portion of the carburetor. The curve C represents the variation in engine suction between the throttle valve 26^a and the engine intake as this valve is open, and the curve D represents the variation in suction within the carburetor bowl. These suction curves are all 115 related to external atmosphere. It is therefore apparent that the force which causes liquid fuel to flow from the bowl 38 through the well 36 and up through the nozzle 32 into the nozzle chamber 25 is due to the difference in suction represented by the curves 120 125

B and D. Now if the carburetor bowl 38 were merely connected with the intake 24 of the carburetor, then it is apparent that the suction in the bowl would be represented by the curve A. Since curve A is steeper than curve D, it is evident that the difference in pressure which causes fuel to flow up through the nozzle would not increase with sufficient rapidity with increasing engine load so that the fuel mixture would tend to run lean as the engine load increases. By adjustment of the needle valve 126, the pressure in the carburetor float bowl 38 can be made to vary according to the curve D so that the rate of increase in pressure differences between the bowl pressure and pressure in the nozzle chamber, will be sufficiently rapid to compensate for any leaning of the fuel mixture proportions which might otherwise occur as the engine load increases.

It is to be understood that the curves shown in Fig. 3 are not to be taken as indicating the exact nature of suction variations in the specific form of apparatus disclosed but are given by way of example to show approximately the relative variations in suction at different points of the apparatus.

While the form of mechanism herein shown and described constitutes a preferred form of embodiment of the invention, it is to be understood that other forms might be adopted, all coming within the scope of the claims which follow.

What I claim is as follows:

1. In a fuel vaporizing device, the combination with an engine having an intake; of a carburetor connected therewith; a suction operated liquid fuel burner discharging into the carburetor for heating the same; and means for automatically restricting the variation of burner suction to a range less than the range of engine suction.

2. In a fuel vaporizing device, the combination with an engine having an intake; of a carburetor connected therewith; a suction operated liquid fuel burner discharging into the carburetor for heating the same; and means for automatically restricting the variation of burner suction to a range less than the variation in engine suction; and manually operated means for controlling said automatic means to vary the rate of burner combustion.

3. In a fuel vaporizing device, the combination with an engine having an intake; of a carburetor connected therewith; a suction operated liquid fuel burner discharging into the carburetor for heating the same; and means for automatically restricting the variation of burner suction to a range less than the variation in engine suction; and manually operated means for controlling said automatic means to vary the rate of burner combustion and for rendering the burner inoperative.

4. In a fuel vaporizing device, the combination with an engine having an intake; of a carburetor connected therewith; a liquid fuel burner for heating the carburetor; said burner being operated by carburetor intake suction; and means for reducing carburetor intake suction below such a value that the burner ceases to operate.

5. In a fuel vaporizing device, the combination with an engine having an intake; of a carburetor connected therewith; a liquid fuel burner for heating the carburetor; said burner being operated by carburetor intake suction; means for regulating carburetor intake suction whereby the range of variation in the rate of burner combustion will be restricted to a value less than the variation in engine suction; and means for controlling said regulating means to vary the rate of burner combustion.

6. In a fuel vaporizing device, the combination with an engine having an intake; of a carburetor connected therewith; a liquid fuel burner for heating the carburetor; said burner being operated by carburetor intake suction; means for regulating carburetor intake suction whereby the range of variation in the burner combustion will be restricted to a value less than the variation in engine suction; and means for controlling said regulating means to vary the rate of burner combustion, and to reduce carburetor intake suction below such a value that the burner ceases to operate.

7. In a fuel vaporizing device, the combination with an engine having an intake; of a carburetor connected therewith; a liquid fuel burner for heating the carburetor intake; said burner being operated by carburetor intake suction; and means for compensating for the delivery of burner products to the carburetor whereby the proportions of oxygen and fuel supplied to the engine intake will remain substantially constant over a relatively wide range of engine load.

8. In a fuel vaporizing device, the combination with an engine having an intake; of a carburetor connected therewith; a liquid fuel burner for heating the carburetor intake, said burner being operated by carburetor intake suction; and means controlling the delivery of fuel from the carburetor bowl through the carburetor fuel nozzle, said means including provisions for compensating for the diluting of air by the burner products whereby the proportions of oxygen and fuel supplied to the engine intake will remain substantially constant of a relatively wide range of engine load.

9. In a fuel vaporizing device, the combination with an engine having an intake; of a carburetor connected therewith; a liquid fuel burner for heating the carburetor intake, said burner being operated by car-

buretor intake suction; and means controlling the delivery of fuel from the carburetor bowl through the carburetor fuel nozzle, said means including provisions for increasing the rate of flow of fuel through said nozzle in such proportions as to compensate for the tendency of the fuel air mixture to become lean with increasing engine load.

10. In a fuel vaporizing device, the combination with an engine having an intake; of a carburetor connected therewith; a liquid fuel burner for heating the carburetor intake, said burner being operated by carburetor intake suction; and a by-pass from the carburetor intake to the engine intake and connected with the carburetor bowl for controlling the delivery of fuel from the carburetor bowl through the carburetor fuel nozzle and including provisions for increasing the rate of flow of fuel through said nozzle in such proportions as to compensate for the tendency of the fuel air mixture to become lean with increasing engine load.

11. In a fuel vaporizing device, the combination with an engine having an intake; of a carburetor connected therewith provided with an intake and a fuel nozzle; a suction operated liquid fuel burner; a regulator located between the burner and carburetor intake for automatically restricting the variation of burner suction to a range less than the variation in engine suction; and a conduit extending through said regulator and along the bottom of the carburetor intake for conducting the products of combustion from the burner to the carburetor intake, said products of combustion impinging upon the fuel collected along the bottom of the carburetor fuel passage.

12. In a fuel vaporizing device, the combination with an engine having an intake; of a carburetor connected therewith; a suction operated liquid fuel burner discharging into the carburetor for heating the same; a regulator located between the burner and the carburetor for automatically restricting the

variation of burner suction to a range less than the variation in engine suction; manually operated means for controlling said automatic means to vary the rate of burner combustion; and means dependent on the operation of said manual means for rendering the burner inoperative.

13. In a fuel vaporizing device, the combination with an engine having an intake; of a carburetor connected therewith; a suction operated liquid fuel burner discharging into the carburetor for heating the same; a regulator located between the burner and carburetor and provided with a plurality of valves normally closed to atmosphere, one of said valves being automatically controlled by engine suction for restricting the variation of burner suction to a range less than the variation in engine suction; and manually operated means for controlling said valve to vary the rate of burner combustion and for operating the other of said valves to render the burner inoperative.

14. In a fuel vaporizing device, the combination with an engine having an intake; of a carburetor connected therewith provided with a fuel nozzle; a liquid fuel burner for heating the carburetor intake, said burner being operated by carburetor intake suction; and a by-pass from the carburetor intake to the engine intake and connected with the carburetor bowl and provided with an adjustable needle valve and a restricted passage for controlling the delivery of fuel from the carburetor bowl through the carburetor fuel nozzle and for increasing the rate of flow of fuel through said nozzle in such proportions as to compensate for the tendency of the fuel air mixture to become lean with increasing engine load.

In testimony whereof I hereto affix my signature.

JOHN H. HUNT.
